UNITED STATES PATENT OFFICE.

ROBERT OGDEN HOFFMAN, OF PENSACOLA, FLORIDA, ASSIGNOR OF ONE-HALF TO
DR. R. A. BROWN, OF PENSACOLA, FLORIDA.

REFRIGERATOR.

Application filed September 27, 1924. Serial No. 740,351.

To all whom it may concern:

Be it known that I, ROBERT O. HOFFMAN, a citizen of the United States, and a resident of Pensacola, in the county of Escambia 5 and State of Florida, have invented certain new and useful Improvements in Refrigerators, of which the following is a specification.

My invention relates to improvements in 10 refrigerators, and it consists in the combinations, constructions and arrangements herein described and claimed.

An object of the invention is to provide a 15 refrigerator which affords facilities for supporting a relatively great number of articles in a refrigerator of a given size so that all the articles will be cooled and the several articles can be removed selectively from the refrigerator quickly and easily without the 20 remaining articles being disturbed during the removal of any one of the articles.

A further object of the invention is the 25 provision of a refrigerator of the character described which is adapted to effect an economy in the use of refrigerant for cooling a given number of articles, in that the liquid dripping from ice within an ice receiving compartment of the refrigerator is subsequently employed to cool other articles.

30 A further object of the invention is the provision of a refrigerator having a rotary cooling carrier for supporting a plurality of articles of the same description or of different descriptions in separated positions and 35 in position to be removed selectively through a single opening when the rotary carrier is rotated in a desired manner, the refrigerator having indicator means whereby the position of any one of the different articles on 40 the carrier with respect to the opening will be indicated.

Other objects and advantages will be apparent from the following description, considered in conjunction with the accompanying 45 drawings, in which—

Figure 1 is a plan view of a refrigerator embodying the invention,

Figure 2 is a front elevation of the refrigerator,

Figure 3 is a vertical central section 50 through the refrigerator, and

Figure 4 is a face view of a label holder which is associated with the refrigerator.

The refrigerator has a casing which comprises a lower section designated generally 55 at 1, and an upper section indicated generally at 2. The lower section preferably is circular in cross or horizontal sectional contour, and comprises a bottom 3, a vertically disposed cylindrical body 4, and a top which 60 consists of an imperforate marginal portion 5 which surrounds a portion which is perforate, as by being formed of spaced apart bars or slats 6. The bottom 3 and the body 4 of the lower section have spaced apart 65 inner and outer walls as shown, between which a suitable heat insulating material, such as cork or the like, and as indicated at 7, is disposed.

The lower section of the refrigerator 70 casing is supported in spaced relation to a floor 8 or like flat supporting surface by any suitable support, such as the vertically disposed annular supporting member 9 having cut-away portions at its lower end as indicated at 10, thus defining legs between the 75 cut-away portions. The bottom 3 of the lower section of the refrigerator rests upon the upper end of the supporting member 9.

The upper section of the refrigerator 80 casing comprises a vertically disposed body 11 which is closed at its upper end by a top 12 and rests at its lower end upon the marginal portion 5 of the top of the lower section so that the center of the top 12 will be disposed directly above the center of the lower section 1 and the space within the upper section 2 will be covered at its lower end by the perforate portion of the top of the lower section. In other words, the bars or 85 slats 6 extend across the space within the upper section 2 at the lower end of the latter, but terminate short of the walls of the body of the upper section so that the body 90 of the upper section may be in fluid tight contact at its lower end with the marginal portion 5 of the top of the lower section 1 inwardly of the outer edge of the latter.

Figure 4 is a face view of a label holder 95 which is associated with the refrigerator.

The body of the upper section may be secured to the marginal portion 5 of the top of the lower section by strips of molding, as indicated at 13 or like means. The body 6 of the upper section preferably is square in cross sectional contour, although it may have any other desirable configuration, and is of less area in cross section than the body of the lower section. The body of the upper 10 section and the top 12 are formed with spaced apart inner and outer walls between which a layer of insulation, as at 14, is placed.

A tubular shaft 15 extends through aligned 15 central openings in the bottom 3 of the lower section and the top 14 of the upper section as well as between adjacent bars 6 of the top of the lower section. The walls of the openings in the bottom 3 and the top 14 20 through which the hollow shaft 15 extends are enlarged at their inner ends for the reception of ball race members 16 which hold ball bearings 17 in rolling contact with the periphery of the tubular shaft 15 so that 25 the latter can be rotated anti-frictionally about its longitudinal axis. A retaining ring 18 which surrounds the tubular shaft 15 is secured to the inner wall of the bottom 3 in position to prevent displacement of the 30 ball race member in the central opening of the bottom 3. A similar retaining ring 19 is secured against the inner wall of the top 14 for retaining the upper ball race member in place. The tubular shaft 15 extends at 35 its lower end below the bottom 3 and at its upper end above the top 14. A stop collar 20 on the tubular shaft above the top 14 is in contact with the latter and holds the tubular shaft 15 against axial movement 40 downward from the position best seen in Figure 3.

A carrier for supporting articles within the lower section of the refrigerator casing is secured to the tubular shaft 15 to rotate 45 with the latter. This carrier is in the form of a pan or tray having an imperforate circular bottom 21 provided with a central opening through which the tubular shaft extends, the wall of the central opening of the bottom 21 and the tubular shaft being 50 secured together to provide a fluid-tight joint therebetween, and so that the bottom 21 will rotate with the tubular shaft. The bottom 21 is circular in configuration and is 55 of slightly less diameter than the body 4 of the lower section of the rectangular casing. A cylindrical body 22 which also is imperforate extends upwardly from the marginal edge of the bottom 21 nearly to the level 60 of the top 5 of the lower section of the refrigerator casing. The cylindrical body 22 may be integral with the bottom 21. It will be manifest that the carrier 21-22 is adapted to hold a liquid and that vessels such as 65 the bottles indicated at 23 and 24 may have

the major portions thereof sub-merged in a cooling liquid 25 in the carrier. The space within the carrier is divided into a plurality of compartments by means of radial partitions 26, each of which is provided with 70 openings as at 27 so that liquid falling into any one of the compartments will pass to the remaining compartment after reaching a certain level in said one compartment. If desired, practically all of the liquid within 75 the carrier may be drained therefrom through a drain opening 28 which establishes communication between the interior of one of the compartments of the carrier and the bore of the hollow shaft 15, the 80 drain opening 28 being located nearly at the level of the lower end of the space within the carrier. A plug 29 normally closes the drain opening 28. A drip cup 30 has inwardly extending lugs 31 at its rim adapted to be hooked over outwardly extending lugs 32 on the lower end of the tubular shaft 15, whereby liquid passing downwardly through the tubular shaft 15 will fill 85 the drip cup and provide a seal for preventing air from passing through the shaft 15 into the interior of the refrigerator through the drain opening 28 when the plug 29 has been removed and at the same time, will not prevent continuous flow of the drain liquid 90 through the tubular shaft 15 and the drip cup 30 to a suitable receptacle, not shown, which may be placed underneath the drip cup.

The portion of the top of the lower section that is located at the front of the refrigerator outwardly of the body of the upper section is provided with an opening which is closed normally by a swinging door 33 as shown in Figure 1, and which is 100 located directly above one of the compartments of the carrier 21-22. It will be apparent that the carrier may be rotated to position the several compartments underneath the opening in the top of the lower section selectively so that a bottle or other article can be removed from any one of the compartments without disturbing the articles within the remaining compartments.

An indicator and operating wheel 34 is 110 secured removably, if desired, as at 35, to the tubular shaft 15 at the upper end of the latter. The wheel 34 is provided with spaced apart outwardly extending handle members 36 which correspond in number 115 and arrangement with the partitions 26 of the carrier, each of the handle members 36 being located directly above and in the plane of the corresponding partition 26. The segmental portion of the rim of the wheel 120 which extends between each two adjacent handle members 36 therefore will lie directly above a particular compartment of the carrier, and may be provided with a label holder such as that indicated at 37, and as 125 130

best seen in Figure 4, the respective label holders supporting labels which bear the names of the articles within the corresponding compartments of the carrier at any given time. For example, liquid commodities of various kinds may be positioned in the compartments of the carrier and the name of each liquid commodity which is supported by the carrier will appear in the 10 label holder or the segmental portion of the rim of the wheel that is located directly above the particular compartment of the carrier in which that particular liquid commodity is supported.

15 A pair of spaced apart index marks 38 are provided on the top of the upper section of the refrigerator casing for cooperating with adjacent handle members 36 to indicate when such handle members respectively are in substantial alinement with the side walls of the opening in the front portion of the top of the lower section of the casing. Therefore, the wheel 34 may be turned, as desired to position any particular 20 compartment of the carrier underneath the opening in the front portion of the top of the lower section so that any particular liquid commodity can be removed conveniently and quickly without disturbing any 25 of the remaining articles which are supported by the carrier.

The level of the cooling liquid within the carrier may be kept nearly constant through the agency of overflow tubes 39. An overflow tube 39 is provided for each compartment of the carrier and which has a form of a substantially U-shaped member arranged with a relatively long arm thereof depending within a compartment of the 35 carrier, the bent portion of the overflow member extending through an opening in the walls of the tubular shaft 15 above the level of the liquid within the carrier, and the shorter arm of the overflow member 40 depending within the bore of the tubular shaft.

The front wall of the body of the upper section 2 is provided with a relatively large opening normally closed by a swingable door 40 and affording access to vertically spaced shelves 41 within an approximate half portion of the body of the upper section. A second opening through the front wall of the body of the upper section is 50 normally closed by a door 42 and permits access to the remaining half portion of the space within the body of the upper section so that a block of ice 43 or like refrigerant may be placed therewithin to rest upon the bars 6.

From the foregoing description of the various parts of the device the operation thereof may be readily understood. The block of ice 43 or like refrigerant within 55 part of the body of the upper section serves

as a means for cooling the articles which may be disposed upon the shelves 41 in the remaining part of the body of the upper section. The relatively cool liquid dripping from the block of ice 43 will fall through the spaces between the bars 6 into the rotary carrier 21-22 and will provide the cooling body of liquid in the latter. The presence of the cooling body of liquid in the carrier will aid in cooling the air which may pass through all parts of the space within the refrigerator at a relatively low temperature. 70

A circular track member 44 is secured upon the bottom 3 of the lower section of the casing and rollers 45 carried by the bottom of the carrier rest upon said track member and are in rolling contact therewith so that the carrier may have relatively easy rotative movement. 75

Obviously, the invention is susceptible of embodiment in forms other than that which is illustrated in the accompanying drawings, and I therefore consider as my own all such modifications and adaptations thereof as fairly fall within the scope of the appended claims. 80

I claim:

1. In a refrigerator, a casing comprising a lower section, an upper section superposed upon the lower section, said lower section being closed at its lower end and being provided at its upper end with a horizontal series of spaced apart slats serving as a bottom for the upper section, a rotary carrier supported within the lower section for rotation about the vertical axis of the casing, said carrier being adapted to hold cooling liquid, and means operable exteriorly of the casing for rotating said carrier. 90

2. In a refrigerator, a casing having a normally closed lateral outlet, a vertical shaft extending through said casing centrally thereof, a rotary carrier comprising a bottom having a central opening through which said tubular shaft extends, and to which said tubular shaft is secured, said carrier including an upstanding marginal body member and a plurality of radial partitions dividing the space in such carrier into a plurality of compartments, said outlet being located above the level of said carrier, the joint between the bottom of the carrier and the tubular shaft being fluid tight and said carrier thus being adapted to hold a cooling liquid, and an overflow pipe leading from the interior of one of said compartments through an opening in the walls of said hollow shaft into the bore of the latter. 100

3. In a refrigerator, a casing having a normally closed lateral outlet, a vertical shaft extending through said casing centrally thereof, a rotary carrier comprising a bottom having a central opening through which said tubular shaft extends, and to which said tubular shaft is secured, said 110

115

120

125

130

- carrier including an upstanding marginal body member and a plurality of radial partitions dividing the space in such carrier into a plurality of compartments, said outlet being located above the level of said carrier, the joint between the bottom of the carrier and the tubular shaft being fluid tight and said carrier thus being adapted to hold a cooling liquid, and an overflow pipe leading from the interior of one of said compartments through an opening in the walls of said hollow shaft into the bore of the latter, said tubular shaft being provided with a drain opening for one of said compartments at about the level of the lower end of the carrier, said drain opening being normally closed.
4. In a refrigerator, a casing comprising a lower section of circular configuration in cross sectional contour, said lower section including a top, said top comprising a substantially imperforate marginal portion and being perforate inwardly of said marginal portion, an upper section superposed upon said lower section of the casing and resting at its lower end upon said imperforate marginal portion of the top of the lower section, the space within the lower section being in communication with the space within the upper section through the apertures in the top of the lower section, said imperforate portion of the top of the lower section having a normally closed opening, said upper section having a normally closed lateral opening through which a block of ice may be placed within the upper section to rest upon the apertured portion of the top of the lower section, a vertical shaft extending through said casing centrally thereof and being rotatable about the vertical axis of the casing, a carrier surrounding the portion of the shaft within said lower section and having the outer edge portion thereof adapted to pass underneath the outlet in the imperforate portion of the top of the lower section as said carrier is rotated, and an operating wheel secured on the upper end portion of said shaft.
5. In a refrigerator, a casing comprising a lower section of circular configuration in cross sectional contour, said lower section including a top, said top comprising a substantially imperforate marginal portion and being perforate inwardly of said marginal portion, an upper section superposed upon said lower section of the casing and resting at its lower end upon said imperforate marginal portion of the top of the lower section, the space within the lower section being in communication with the space within the upper section through the aperture in the top of the lower section, said imperforate portion of the top of the lower section having a normally closed opening, said upper section having a normally closed lateral opening through which a block of ice may be placed within the upper section to rest upon the apertured portion of the top of the lower section, a vertical shaft extending through said casing centrally thereof and being rotatable about the vertical axis of the casing, a carrier surrounding the portion of the shaft within said lower section and having the outer edge portion thereof adapted to pass underneath the outlet in the imperforate portion of the top of the lower section as said carrier is rotated, an operating wheel secured on the upper end portion of said shaft, radial partitions dividing said carrier into a plurality of compartments, handle members extending radially outward from the rim of said wheel and corresponding in number and position with the partitions of said carrier, and means for supporting labels between each two adjacent handle members, said upper section having index marks on the top thereof for cooperating with each set of two adjacent handle members to indicate the positions of the respective compartments of the carrier in respect to the outlet in the imperforate portion of the top of the lower section.
6. In a refrigerator, a casing comprising a lower section of circular configuration in cross sectional contour, said lower section including a top, said top comprising a substantially imperforate marginal portion and being perforate inwardly of said marginal portion, an upper section superposed upon said lower section of the casing and resting at its lower end upon said imperforate marginal portion of the top of the lower section, the space within the lower section being in communication with the space within the upper section through the apertures in the top of the lower section, said imperforate portion of the top of the lower section having a normally closed opening, said upper section having a normally closed lateral opening through which a block of ice may be placed within the upper section to rest upon the apertured portion of the top of the lower section, a vertical shaft extending through said casing centrally thereof, and being rotatable about the vertical axis of the casing, a carrier surrounding the portion of the shaft within said lower section and having the outer edge portion thereof adapted to pass underneath the outlet in the imperforate portion of the top of the lower section as said carrier is rotated, an operating wheel secured on the upper end portion of said shaft, radial partitions dividing said carrier into a plurality of compartments, handle members extending radially outward from the rim of said wheel and corresponding in number and position with the partitions of said carrier, and means for supporting labels between each two adjacent handle members, said upper section having index marks on the top thereof for cooperating with each set of two adjacent handle members to indicate the positions of the respective compartments of the carrier in respect to the outlet in the imperforate portion of the top of the lower section.

7. In a refrigerator, a casing having a normally closed lateral outlet, a vertical shaft extending through said casing centrally thereof, a rotary carrier supported within the casing on said shaft to rotate about the axis of the shaft, a plurality of radial partitions dividing said carrier into a plurality of compartments, handle mem- bers extending radially outward from the upper end of said shaft and corresponding in number and position with the partitions of said carrier, and means between each two adjacent handles for supporting indicia for indicating the article within the corresponding compartment of the refrigerator.

ROBERT OGDEN HOFFMAN.
